UNITED STATES PATENT OFFICE.

ALEXANDER F. ARMSTRONG, OF EDINBURG, AND MILO K. WAITE, OF NORTHVILLE, NEW YORK; SAID WAITE ASSIGNOR TO LEWIS BALCH, OF ALBANY, NEW YORK.

HORSE-BLANKET FASTENER.

SPECIFICATION forming part of Letters Patent No. 290,198, dated December 18, 1883.

Application filed June 13, 1883. (No model.)

To all whom it may concern:

Be it known that we, ALEXANDER F. ARMSTRONG and MILO K. WAITE, citizens of the United States, residing, respectively, at Edinburg, in the county of Saratoga and State of New York, and at Northville, in the county of Fulton and State aforesaid, have invented a new and useful Horse-Blanket Fastener, of which the following is a specification.

10 The object of our invention is to make a simple, strong, and durable fastener for horse-blankets and the like by constructing the said fasteners from steel or brass spring-wire, so that they may be attached to the fabrics by 15 any of the known methods with facility. We attain this object by the mechanism illustrated in the accompanying drawings, in which—

Figure 1 is a face plan view of the two flaps of a horse-blanket with our invention attached. 20 Fig. 2 is a lateral elevation of the spring-hasp and securing-rivet, and Fig. 3 is a top plan view of the eye-piece detached. The arrows indicate the direction of the spring-pressure of the bifurcated hasp.

25 Similar letters refer to similar parts throughout the several views.

A A' represent the two edges or flaps of a horse-blanket; B, the bifurcated hasp; C, the eye-piece, which receives and retains at pleasure the bifurcated hasp B.

d d d d are rivets which secure the fasteners to the horse-blanket, as shown in Figs. 1 and 2.

e e are loops formed in the two arms of the hasp B, to facilitate their compression in the act of hasping and unhasping of the two parts 35 constituting the fastener.

f f, Fig. 3, are eyes formed in the parts for their attachment to the horse-blanket by means of the rivets d d d d, as shown.

g g are the upward and outward bent or 40 double-curved hooks of the outward-springing arms h h, whose curves correspond with the retaining-surfaces of the eye-piece C, as will be readily understood. The arms h h, having an outward pressure, tend to keep securely locked or interlocked with the eye-piece until released by lateral pressure applied to the arms, which releases the hooks g g from the eye-piece C, as will be readily inferred.

What we claim as new, and desire to secure 50 by Letters Patent, is—

The combination, in a horse-blanket fastener having outward-springing arms h h, provided with double-curved hooks g g, of spiral loops e e and eye-piece C, all substantially shown 55 and described.

ALEXANDER F. ARMSTRONG.
MILO K. WAITE.
